FREE PISTON TYPE INTERNAL-
COMBUSTION COMPRESSOR

Robert James Welsh and Alec Benjamin Fitz
Herbert, Rugby, England, assignors to The Eng-
lish Electric Company Limited, London, Eng-
land, a British company

Application January 22, 1946, Serial No. 642,612
In Great Britain January 25, 1945

1 Claim. (Cl. 230—56)

1

This invention relates to a free piston type internal combustion compressor—i. e. a device wherein a compressor piston is directly connected to or combined with an internal combustion engine piston and wherein the motion of these pistons is not constrained by coupling through connecting rods and cranks to rotating members. There are usually two opposed engine pistons reciprocable towards and away from each other in one cylinder. The engine is usually one which operates on a two-stroke compression-ignition cycle, some or all of the air from the compressor serving to scavenge and charge the engine cylinder.

A device of this kind may be used as a gas-generator to supply another piece of apparatus such as a gas turbine which may have as its working fluid either (i) solely air coming direct from the compressor or (ii) solely the exhaust from the engine cylinder (comprising the products of the combustion in the engine cylinder mixed with the scavenging air supplied to the engine by the compressor) or (iii) a mixture of the engine exhaust with air coming direct from the compressor. The second of these three alternatives is most usual.

A free-piston internal combustion operated compressor according to the invention has a single-acting compressor with a closed idle space, and means are provided which tend, under normal running conditions, to equalize the mean effective pressure on the idle side of the compressor piston with the pressure at the inlet to the compressor cylinder. The invention will be described with reference to the accompanying drawings, in which Fig. 1 shows a diagrammatic elevation, partly in section on the axis, of a device embodying the invention arranged as a gas generator for a gas turbine, while Fig. 2 is a diagram of the pressure in the idle space depending on the position of the equalising means.

The body of the free piston type internal combustion compressor shown in Fig. 1 comprises a single engine cylinder 1, a pair of compressor cylinders 2 at opposite ends thereof and a pair of buffer cylinders 3 at the extreme outer ends of cylinders 2. Within the engine cylinder 1 a pair of opposed engine pistons 4 reciprocate synchronously in opposition to each other. Each of these pistons 4 forms a free piston unit with one of the compressor pistons 5 reciprocating in a cylinder 2 and with one of the buffer pistons 6 reciprocating in a cylinder 3. The head of each of the compressor cylinders 2 is provided with at least one non-return inlet valve 12 and at

least one non-return discharge valve 13. The inlet valve 12 puts the compressor space 2a of compressor cylinder 2 in communication with inlet chamber 14a, while the discharge valve 13 puts this compressor space 2a in communication with discharge chamber 15a. The discharge chamber 15a is continuous with conduit 15 which transfers the compressed air to the annular space 15b surrounding the ring of inlet ports 1a in the engine cylinder 1. The exhaust conduit 16 from the engine cylinder 1 carries the mixture of scavenging air and combustion products to feed a gas turbine 25.

Fuel is injected into the cylinder 1 by fuel injectors 9 supplied through fuel pipe 11, distributor 18 and fuel pipes 19, from the fuel injection pump 10. The quantity of fuel injected for each cycle of the engine is determined by the position of its fuel rack 10a. This fuel rack is controlled through rods 31 and bell cranks 36 by the governor 28 of the turbine 25, so as to decrease the fuel supply per cycle when the turbine speed rises. At the same time the turbine governor controls throttles 32 in the inlet conduits 14 so as to tend to close these throttles when the turbine speed rises.

While the pistons are making an out-stroke under the influence of the pressure due to combustion in engine cylinder 1, the air trapped in compressor space 2a is compressed and partially discharged through valve 13. The air trapped in buffer cylinder 3 is not discharged, but is compressed and serves, together with the residual compressed air in compressor space 2a, to return the pistons so that they make an in-stroke and compress the air in engine cylinder 1.

Each of the compressor cylinders 2 is single-acting, that is to say, only the space 2a on one side—the outer side—of compressor piston 5 is used to supply compressed air. The space 2b on the other side is an idle space. If this idle space 2b were left open to the atmosphere, considerable energy would be expended every cycle in pumping air in and out of it. In this arrangement this idle space is closed so that, during normally running, the air trapped therein is compressed on every in-stroke and expands on every out-stroke. If the pressure in this idle space 2b at the end of the out-stroke were made equal to that in the compressor inlet chamber 14a, the effect of the compression in the idle space 2b during the in-stroke would be to oppose the action of buffer piston 6. If, on the other hand, the pressure in this idle space 2b at the end of the in-stroke were made equal to that in

the compressor inlet chamber 14a, the effect of the expansion in the idle space 2b during the out-stroke would be to assist the action of buffer piston 6 on the following in-stroke.

This opposition or assistance to the action of the buffer piston cannot altogether be offset simply by changing the size of the buffer cylinder, because the pressure/stroke characteristic of the idle space will be quite different from that of the buffer cylinder and the variations with varying position of outer dead centre due to change in working conditions will therefore tend to become unmanageable.

In the present arrangement, these difficulties which arise when the idle space 2b is closed are overcome by the provision of means which ensure that the net work done on any single inward or outward stroke is zero. To achieve this result, the mean effective pressure in the idle space is made substantially equal to the pressure at the compressor inlet, which pressure, if a throttle is employed as at 32, will usually be below atmospheric. The point on the compression/expansion curve of the idle space where this mean effective pressure equals the compressor inlet pressure will be situated at approximately mid-stroke, consequently the terminal pressures corresponding to the inner and outer dead point positions will be above and below the compressor inlet pressure respectively. Therefore during an outward stroke and from the inner dead point to approximately mid-stroke, positive work will be done on the idle face of the compressor piston while from mid-stroke to the outer dead point, negative work will be done on it. By proper dis-positioning of the parts it is possible to make the negative work equal the positive work so that the net work done is zero. During an inward stroke the order will be reversed but the net work done will again be substantially equal to zero.

Thus, if the relationship between stroke and pressure in the idle space be represented by a diagram after the fashion of an ordinary indicator card, then the compression and expansion line of the idle space would be so disposed in relation to the atmospheric line that if a perpendicular were dropped from the atmospheric line at each end of the stroke then the area of the indicator diagram above the atmospheric line at one end of the stroke would be equal to the area of the indicator diagram below the atmospheric line at the other end of the stroke. This will be explained more in detail with reference to Fig. 2.

In the arrangement shown in Fig. 1, a port 50 in the wall of cylinder 2 is connected to the compressor inlet chamber 14a through a non-return valve 51. The port 50 is situated near mid-stroke of the inner edge 5b of the skirt of compressor piston 5 so that on an outward stroke it is closed by this piston during the whole of the travel from the inner dead point to approximately mid-stroke (hereinafter termed the inner half-stroke) and is opened to the idle space 2b during the remainder of the stroke (hereinafter termed the outer half-stroke). During an inward stroke, the port 50 will of course be open to the idle space 2b during the outer half-stroke and closed during the inner half-stroke. The precise position of port 50 will be as nearly as possible opposite the point which is reached by the edge 5b of the piston skirt at the instant in the piston stroke when, under normal working conditions, the instantaneous pressure on the idle side of the piston 5 is equal to the mean effective pressure

thereon taken over the whole stroke. During the inner half stroke when port 50 is closed by piston 5, the pressure in idle space 2b is above that in inlet chamber 14a; but during the outer

half stroke when port 50 is uncovered, the pressure in idle space 2b is lower than that in inlet chamber 14a and the non-return valve 51 therefore remains closed. If, however, the quantity of air in idle space 2b at any time is above the proper value, so that the mean effective pressure exceeds the pressure in the inlet chamber 14a, then non-return valve 51 will open for a short period after port 50 is uncovered, and will permit the excess air to escape into inlet chamber 14a. In order to increase gradually the quantity of air in idle space 2b when it is below the proper value, one or more small leaks are provided, unless the natural leakage is adequate. Such leaks are indicated (a) at 52 in the non-return valve 51, (b) at 53, leading to atmosphere, and (c) at 54 leading into the scavenging air space 15b. Only one of these leaks will normally be provided, and in that case it may take any of the positions 52, 53, 54.

25 Operation

An additional non-return valve 55 is arranged to lead from the idle space 2b into the scavenging air space 15b. During normal running of the compressor, the maximum pressure in idle space 2b does not exceed the discharge pressure of the compressor, which is also approximately the pressure present in scavenging air space 15b, and this valve 55 therefore remains closed. During starting, however, the discharge pressure of the compressor cylinder may be approximately equal to atmospheric pressure. Before each attempt to start the engine, it is usually barred to the end of an out-stroke, and an in-stroke may then be initiated by admitting compressed air to buffer cylinder 3. The idle space 2b may be full of air at atmospheric pressure before the in-stroke commences. During the first half of the in-stroke, until port 50 is covered, air will escape from the idle space through port 50 and non-return valve 51 into inlet chamber 14a. If port 50 is large, therefore, the pressure in the idle space 2b when port 50 becomes covered will be approximately atmospheric. Thereafter, however, it will tend to rise and to produce an unwanted compression pressure which will oppose the action of the starting air admitted to buffer cylinder 3. The non-return valve 55 relieves this pressure during this stroke, and similarly relieves it to a gradually decreasing degree during successive strokes as pressure is gradually built up in the scavenging air space 15b. The release of air from the idle space through relief valve 55 is not fully compensated by inward leakage through leaks 52, 53, 54 until a considerable number of cycles of engine operation have occurred. During this time, the idle space has a mean effective pressure substantially below the pressure in inlet chamber 14a and therefore assists the buffer cylinder in returning the pistons on their in-stroke. When normal running conditions have been reached, the valve 55 will remain closed, and the port 50 and non-return valve 51 will operate in the manner previously described to neutralise the effect of the air trapped in the idle space 2b. The balance of the return energy provided by the buffer cylinder 3, and the residual compressed air in the space 2a will not therefore be disturbed as would otherwise be the case.

75 The effect of the position of the port 50 is illus-

trated in Fig. 2, parts (a), (b) and (c) of which represent the indicator diagrams obtaining in the idle space when (a) the port 50 in the compressor cylinder wall is situated too near to the inner dead point (I. D. P.) position of the piston, (b) when the port is in the correct desired position near to mid-stroke and (c) when it is displaced towards the outer dead point (O. D. P.) position.

Every time the port 50 connects the idle space 2b to the inlet chamber the pressures in the two will be at least approximately equalised, therefore the initial pressure p_1 of the subsequent compression or expansion, according as to whether the piston is moving inwards or outwards, will be the pressure in the inlet chamber. From (a) it will be seen that with the port situated towards the I. D. P., the compressive or positive work, +, done in the idle space is much less than the expansive or negative work, -, and that the mean effective pressure p_m represented by the dotted horizontal line lies well below the inlet pressure p_1 . With (b) the position of the port has been correctly chosen and in this case the mean effective pressure p_m coincides with the pressure p_1 at the inlet, with the result that the positive and negative work areas + and - are equal. (c) represents the case when the port 50 is situated too far towards the outer dead point (O. D. P.) position (and here the positive area, +, of the diagram is much in excess of the negative area, -). The mean effective pressure p_m in this case lies well above the inlet pressure p_1 .

These diagrams show therefore that there is only one point at which the port 50 can be situated to meet the requirement that it is in operation at or about the instant when the pressure in the idle space corresponds to the mean effective pressure.

What we claim as our invention and desire to secure by Letters Patent is:

A free piston internal combustion engine operated compressor or gas generator comprising an engine cylinder, at least one single acting ported compressor cylinder, at least one free piston assembly adapted to reciprocate in the said cylinders and comprising an engine piston and

a compressor piston, a closed idle space formed by the said compressor piston and cylinder on the non-working side of the compressor piston, a compressor inlet duct, a port in the wall of the said ported compressor cylinder adapted to be uncovered by the compressor piston at a point corresponding substantially to mid-stroke, a duct connection between said port and said inlet duct and an outwardly opening automatic non-return energy equalizing valve adapted to close the said port against the air inlet pressure when the said pressure is greater than that in the said idle space, a scavenge chamber intermediate the said idle space and the said engine cylinder wherein the pressure during normal running of the compressor or gas generator remains continuously above the maximum pressure in the said idle space but wherein the pressure during starting of the compressor or gas generator is below said maximum, a connection between said idle space and said scavenge chamber and a non-return starting relief valve in said connection, said starting relief valve being adapted to permit flow in the direction from the said idle space to said scavenge chamber and thereby to relieve compression pressure in the said idle space during starting.
